(57) **CLAIM**

The ornamental design for a storage saddle for computer tower, as shown and described.

DESCRIPTION

FIG. 1 is a perspective view of a storage saddle for computer tower embodying the design of the present invention; FIG. 2 is a front elevational view thereof; FIG. 3 is a rear elevational view thereof; FIG. 4 is a left side elevational view thereof; the right side elevational view being a mirror image thereof; FIG. 5 is a top plan view thereof; FIG. 6 is a bottom plan view thereof; and, FIG. 7 is a perspective view showing the storage saddle for computer tower in use; the broken lines depict environmental structure and form no part of the claimed design.
